[57] CLAIM

The ornamental design for a support for an infant, as shown and described.

DESCRIPTION

FIG. 1 is a perspective view of a support for an infant, showing my new design, in exploded condition;
FIG. 2 is a top plan view thereof;
FIG. 3 is a side elevational view thereof, the rear elevational view being a mirror image thereof; and,
FIG. 4 is a top plan view of a support for an infant, showing an alternate embodiment of my new design.
The bottom of the article is plain and unadorned.
